(57) **CLAIM**

The ornamental design for a motorcycle-to-trike conversion kit adapter, as shown and described.

DESCRIPTION

FIG. 1 is a perspective view of the motorcycle-to-trike conversion kit adapter according to the present invention. FIG. 2 is a top view of the motorcycle-to-trike conversion kit adapter according to the present invention.

FIG. 3 is a front view of the motorcycle-to-trike conversion kit adapter according to the present invention. The rear view is a mirror image of the front view view.

FIG. 4 is a left side view of the motorcycle-to-trike conversion kit adapter according to the present invention.

FIG. 5 is a right side view of the motorcycle-to-trike conversion kit adapter according to the present invention; and,

FIG. 6 is a bottom view of the motorcycle-to-trike conversion kit adapter according to the present invention.
